UNITED STATES PATENT OFFICE

JOSEPH ALBON BASCLE, OF PONCHATOULA, LOUISIANA

INTERNAL COMBUSTION ENGINE

Application filed June 17, 1930. Serial No. 461,779.

The present invention relates to the art of internal combustion engines, and has far an object to provide certain structural improvements and combinations relating to an engine of the two-cycle type.

Another object of the present invention is to provide an engine of the two-cycle type which for its weight and fuel consumption will produce a maximum of power, a relatively high engine speed, better balance, lighter weight per horse power, less moving parts than in engines heretofore constructed of this type, and to provide an engine which has longer life, a quietness of moving parts and complete vaporizing of gas mixture.

With the foregoing and other objects in view, the invention will be more fully described hereinafter, and will be more particularly pointed out in the claims appended hereto.

In the drawings, wherein like symbols refer to like or corresponding parts throughout the several views.

Figure 1 is a side elevation of an internal combustion engine constructed according to the present invention.

Figure 2 is a vertical longitudinal section taken through the same.

Figure 3 is an enlarged detail section taken through the blower.

Figure 4 is a detail perspective view of the inner rotary part of the blower with the blades removed.

Figure 5 is a detail fragmentary sectional view of the outer wall of the blower casing, showing one of the blades of the blower in position thereagainst.

Figure 6 is a horizontal section taken through the upper part of the motor, showing the pressure regulating means and the intake manifold.

Figure 7 is a transverse section taken through the same, and showing the pressure relief means, and

Figure 8 is a fragmentary enlarged sectional view taken through one of the cam wheels, showing the detachable cam mounted thereon.

Referring now to the drawings, and more particularly to Figure 2, 15 designates a

crank shaft which is of general conventional construction and provided with an intermediate and opposite end bearing portion adapted to engage in an intermediate bearing 16 and in the opposite end bearings 17 and 18 of a crank case 19. The forward end of the crank shaft 15 is provided with a belt pulley 20 which may be of the usual V-type and which is keyed or otherwise suitably fixed to the crank shaft 15 and held in place by a ratchet nut 21 used for connecting a detachable crank handle to the crank shaft when it is desired to manually turn the same.

The crank shaft 15 is also provided near its forward end, and forwardly of the first crank arm, with a cam wheel 23, shown in detail in Figure 8, and wherein the body portion of the wheel is in the form of a disc mounted on the shaft 15 and provided in one edge portion with a dove tail seat or depression extending entirely across the width of the cam wheel 23 and adapted to receive therein the correspondingly dove tailed shape base portion 24 of a cam 25 which is driven laterally into place. This cam 25 may be made of material which is relatively hard as compared with the material of the cam wheel 23. The cam 25 may be removed from the cam wheel when the cam is worn so that the cams are readily interchanged.

The rear end portion of the crank shaft 15 is provided with a second cam wheel 23 having a cam 25 thereon, and these cams and cam wheels are adapted to control the rise and fall of push rods 26 which control the operation of intake valves as hereinafter pointed out. A flywheel 27 is mounted upon the rear end of the crank shaft 15 and the crank shaft is suitably connected to a drive shaft or the like depending upon the particular use for which the engine is constructed.

The crank case 19 carries a cylinder block which in the present instance is provided with two cylinders 28 opening upwardly through the block and closed by a cylinder head 29 bolted or otherwise suitably secured upon the cylinder block. The head 29 is provided with a shallow concavity in its underside adapted to register with the upper

end of each cylinder 28 when the head is in place. Each cylinder 28 is provided therein with a piston 30 of suitable length, allowing same to seal exhaust port when in upward position, and which is provided with the usual piston rings near its upper and lower ends, the latter for the purpose of sealing the exhaust port 33 when the piston is in a raised position. It will be noted that the exhaust port 33 is relatively large and extends for a considerable distance in one side of the cylinder 28, and that the wall through which the exhaust port 33 is formed is reinforced by the provision of webs or bars 34 which divide the exhaust port up into a plurality of separate passages.

The cylinder block is provided with the usual water jacket 35 and is also provided with guide tubes 36 at opposite ends of the block for enclosing the push rods 26 and also for returning oil from the head 29 back into the crank case 19. The lower end of each push rod 26 projects into the upper portion of the crank case 19 and is provided with a suitably shaped end adapted to seat in a valve lifter cup 37 provided with a depending shank slidably engaging through a valve lifter guide 38, and which at its lower end is adapted to bear against the cam wheel 23 and the cam 25. A relief spring 39 encircles the shank of the valve lifter cup 37 for normally urging the same upwardly and maintaining it in contact with the lower end of the push rod 26.

The crank shaft 15 is provided, adjacent to the rear cam wheel 23, with a spiral gear wheel 40 which meshes with a worm 41 on a shaft 42 which extends upwardly and through the crank shaft 19 for connection with a distributor 43 to drive the latter. Connected to each crank portion of the shaft 15 is a connecting rod 44. Each rod 44 extends upwardly into the adjacent cylinder 28 and is connected to the respective piston 30 in the usual manner. The gear wheel 40 in the crank case is arranged to drive an oil pump 46 preferably located in the bottom of the crank case 19 and connected to the lower end of the shaft 42.

The push rods 26 are provided on their upper ends with sockets or depressions 47 into which engage balls 48 on the outer end of the rocker arms 49. The rocker arms are pivotally mounted intermediate their ends upon brackets 50 carried by the said head 29 of the engine, and the free ends of said arms 49 bear against the upper ends of valve stems 51 held normally in raised position by springs 52. The stems 51 extend inwardly through the head 29 and have valve discs 53 upon their inner ends adapted to seat over intake openings 54 extending through the head 29.

The rocker arms 49 are housed within a hood 55 which is mounted on the head 29 of

the engine for enclosing the rocker arms and confining oil fed thereto from leaving the arms 49 and adjacent parts so that the oil accumulating in the head 29 may pass off through the tubes 36 and back into the crank case 19.

The rocker arms 49, and other adjacent parts of the valves, are enclosed within a hood 55, Figure 1, which has a flanged opening 56 at its rear end to which an air cleaner may be attached, and at its other end has a flanged opening 57 for connection with a carburetor 58, of any suitable type, and which in turn is connected to the rear side of a blower casing 59.

The blower is of suitable size and preferably cylindrical in general configuration. The blower is mounted upon a bracket 60 which extends forwardly from the cylinder block of the engine for holding the blower in proper position so that the shaft 61 of the blower provides at its outer end a support for the fan 62 adapted to cool the engine. Between the fan 62 and the casing 59, the shaft 61 is provided with a pulley 63 over which passes a drive belt 64 which is driven from the pulley 20 on the crank shaft 15.

As best shown in Figures 3, 4 and 5 the blower casing 59 is positioned eccentrically upon the shaft 61 and the latter has secured to it a rotor or inner rotating member 65 in the form of a cylindrical block which slidably carries a plurality of blades 66. The blades 66 are relatively flat and are of substantially the width of the interior of the casing 59 and are of a length adapted to entirely recede into slots 67 which are formed at spaced intervals in the periphery of the block 65. These slots 67 extend entirely through the opposite sides of the block and are arranged substantially at a tangent with respect to the shaft 61. The blades 66 freely slide in the slots 67 so that by centrifugal force these blades are urged outwardly against the inner wall of the casing 59 so as to seal the blades 66 thereagainst and create the desired pumping action.

It will be noted from Figure 3 that the carburetor 58 is connected to one side of the casing 59 while the opposite side of the casing has a connection 68 adapted to receive one end of a coupling 69 which leads to the forward end of a manifold chamber 70. This chamber 70 is bored in the left upper portion of the cylinder block and extends throughout the length of the head. Intermediate the end of the chamber 70 is a divided manifold passage 71 which leads through the head 29 and communicates with the intake passages 54 for feeding fuel under pressure to the cylinders 28.

The intake chamber 70 is provided with a ringed piston 73, the latter adapted to receive the pressure of the fuel from the blower

thereagainst. The piston 73 is maintained yieldingly in a forward position by a spring 74 bearing at its inner end against the piston 73 and seated in its outer end in a cup 75 carried on the inner end of a threaded rod 76 which is adjustably mounted through a disc 77 screwed into the outer end of the cylinder 72.

A lock nut 78 is carried by the rod 76 for engagement against the disc 77 to lock the rod 76 from movement when adjusted. The cylinder 70 is provided at a suitable rear point, and in one side, with an exhaust port 79 of suitable size for venting the fuel chamber 70 when the pressure is raised sufficiently to force the piston 73 backwardly to an extent such that the port 79 will be open to the chamber 70.

By adjustment of the spring 74 the pressure in the fuel chamber may be maintained substantially constant and the piston 73 will effectively relieve the sudden abnormally increased pressure upon back-fire in the engine.

A suitable butterfly or throttle valve 80 may be mounted in the forward end of the fuel chamber 70 for controlling the passage of fuel to the manifold 71. The outer edge portion of each blade 66 may be provided with a suitable packing slip, or brass filler 82 there-in adapted to bear against the inner wall of the casing 59 of the blower, as shown in Figure 5, for more effectively sealing the blade in the casing.

The forward part of the crank case 19 is provided with a laterally disposed bracket 83 supporting a generator shaft 84 equipped with a pulley 85 which bears against the inner side of the belt 64 so that the generator may be driven directly from the main pulley 20 on the crank shaft.

As shown in Figure 1, the crank case 19 carries at one side a water pump 86, the shaft of which is connected to the rear end of the generator shaft 84 which acts as its means of propulsion. The pump is provided with a feed pipe 88 which is carried upwardly to the jacket 35, and is also provided with a return pipe 89 which leads to the radiator, not shown, the water flowing through the radiator and cooling system in the usual manner.

The engine is equipped with spark plugs 90 which are grounded at one side in the engine in the usual manner and which at their other sides are connected to the high tension wires 55 91 which lead to the distributor 43.

In operation, the parts of the engine function in the general ordinary manner, and the crank shaft 15 in turning operates the gear 40 and also the cams 23 so as to control the opening and closing of the intake valves 53, the operation of the oil pump and distributor. The pulley 20 on the crank shaft 15 drives the belt 64 which operates the generator and water pump through the pulley 63 and also drives the fan 62 and the blower which is

mounted on or connected to the cam shaft 61.

The blower draws in a gas mixture through the carburetor 58, the latter being supplied with warm air which passes through the hood 55 and an air cleaner or the like which may be mounted upon the connection 56. The blower delivers the mixture through the connection 69 to the intake passage 70 and intake manifold 71, the pressure remaining constant incident to the operation of the spring pressed piston or plunger 73 and, by adjustment of the tension of the spring 74 the desired pressure of the fuel mixture may be maintained in the manifold 71.

As pressure is maintained at all times in the intake manifold, the mixture is maintained under pressure in the passage 54 so that when the intake valves 53 are opened the mixture under pressure is delivered into the upper ends of the cylinders 28. The intake valves 53 are timed to admit the mixture under pressure at the instant the piston 30 closes the exhaust passage going upwards in the cylinder 28. The admixture is admitted to the upper end of the cylinder 28 during approximately one-fourth of the upward stroke of the piston 30. The intake valve 53 now closes, the piston continues its upward stroke and compresses the admixture in the upper end of the cylinder 28 until the piston reaches substantially the top or dead center position when the spark is produced at the plug 90, effecting an explosion and driving the piston 30 downwardly, the pressure continuing against the piston until the latter uncovers the exhaust opening or openings 33 at which time the burnt gases are expelled. The exhaust openings 33 are maintained open during the further downward movement of the piston 30, and also until the piston rises to approximately one-fifth of its stroke, at which time the piston overlaps the exhaust ports or openings 33 and closes the same.

It is apparent that upon back-fire in the engine, or undue pressure in the blower, the spring supported plunger 73 yields and is driven backwardly or outwardly a distance sufficient to uncover the exhaust port 79 whereupon the excess pressure in the manifold and in the feed passage 70 is vented or relieved, and the plunger 73 is again thrust inwardly or forwardly to maintain the normal pressure in the manifold 71.

The blower may be proportioned or regulated as to speed dependent upon the needed volume, and this may be varied to suit the best operating pressure according to the size and proportions of the parts of the engine.

It is obvious that various changes and modifications may be made in the details of construction and design of the above specifically described embodiment of this invention without departing from the spirit thereof, such changes and modifications being restricted only by the scope of the following claims.

What is claimed is:—

1. In an internal combustion engine, a body portion having a cylinder therein, a piston mounted in the cylinder, a crank shaft mounted in the body portion connected to said piston, a blower mounted on the body portion and connected to the crank shaft and adapted to be driven thereby, an intake valve on the upper end of the body portion opening into the top of said cylinder, connections between the intake valve and the crank shaft for operating the intake valve at stated intervals, a hood mounted on the upper end of the body portion and enclosing said intake valve and its connections and having an air intake opening at one end and a carburetor connection at its opposite end, a carburetor arranged between said carburetor connection of the hood and the intake side of said blower, said body portion having an intake manifold leading to said valve and provided with an intake passage connected to the outlet side of said blower whereby operation of said blower draws air in through said hood to heat the air and through said carburetor to the blower and delivers the mixture under pressure to said passage and intake manifold, and means in said passage for maintaining a constant pressure of the mixture fed to the manifold.
2. In an internal combustion engine, a body portion having a cylinder therein, a piston mounted in the cylinder, a crank shaft mounted in the body portion connected to said piston, a blower mounted on the body portion and connected to the crank shaft and adapted to be driven thereby, an intake valve on the intake end of the body portion opening into the top of said cylinder, connections between the intake valve and the crank shaft for operating the intake valve at stated intervals, a hood mounted on the upper end of the body portion and enclosing said intake valve and its connections and having an air intake opening at one end and a carburetor connection at its opposite end, and a carburetor arranged between said carburetor connection of the hood and the intake side of said blower, said body portions having an intake manifold leading to said valve and provided with an intake passage connected to the outlet side of said blower whereby operation of said blower draws the air in through said hood to heat the air and through said carburetor to the blower and delivers the mixture under pressure to said passage and intake manifold.
3. An internal combustion engine having a body portion provided with a cylinder, an intake valve for the cylinder, a hood mounted over the cylinder and having an air inlet opening, a blower, a carburetor between the intake side of the blower and said hood, an intake member between the valve and the outlet side of the blower, whereby the blower draws air through the hood to heat the air and

through the carburetor and supplies the intake member with the heated mixture.

4. In an internal combustion engine, a body portion having a plurality of cylinders therein, intake valves for the cylinders, a hood mounted on the body portion and extending over all of said cylinders and having an air inlet opening at one end, a blower connected to the opposite end of the hood, a carburetor interposed between the blower and the hood, an intake manifold arranged between the outlet side of the blower and said body portion and opening into said intake valves, whereby the blower is adapted to draw air through the hood to heat the air and through the carburetor and supplies the manifold with the heated mixture.
